PROCESS OF MANUFACTURING CARBURETED WATER GAS

Filed June 30, 1944

UNITED STATES PATENT OFFICE

2,537,242

PROCESS OF MANUFACTURING
CARBURETED WATER GAS

Kenneth W. Stookey, Cleveland, Ohio, assignor
to The Gas Machinery Company, Cleveland,
Ohio, a corporation of Ohio

Application June 30, 1944, Serial No. 542,862

6 Claims. (Cl. 48—205)

1

The instant application is a continuation in part of my pending applications Serial Nos. 455,184 and 455,185, filed August 18, 1942, now abandoned, and the invention disclosed therein relates to improvements in well-known methods of manufacturing carbureted water gas in a gas-making set including a generator, carbureting apparatus (usually a carburetor and a superheater and so herein shown and described), and a seal, all connected in a well-known manner, and equipped with the usual fixtures, such as pipes and valves, for supplying suitable media for upwardly blasting a fuel bed in the generator, and for making up and down gas-making runs through the fuel bed, and for carbureting the water gas so made. Certain well-known methods of manufacturing carbureted water gas also include a reverse or down-blasting which is effected by admitting blasting air to the top of the generator. Certain well-known methods of manufacturing carbureted water gas include the use of heavy oil, such as bunker oil, for the carbureting medium, which heavy oil is sprayed upon the top of the fuel bed. Preferably, the working of the instant improved methods of carbureted water gas manufacture is effected in procedures in which heavy oil is used as a carbureting medium and in which a down blasting of the generator fuel bed is practiced as a part of the cycle of operations.

The aforescribed well-known methods of manufacturing carbureted water gas do not serve to keep the top of the generator fuel bed sufficiently hot when a soft fuel, such as bituminous coal, petroleum coke, a combination of petroleum coke and an asphalt binder, or a coal and coke mixture, is used as a generator fuel. The carbureting medium, particularly when it is heavy oil, which is sprayed into the top of the generator during the run, has a cooling effect which is not counterbalanced by the usual air-blasting. Therefore, the improvements of the instant application consist in a procedure which creates additional heat in the top of the generator, after a charging of fresh fuel and prior to the blasting phase of the subsequent cycle, thus assisting in carbonizing the upper part of the soft fuel charged into the generator and in preparing the generator fire for spraying the carbureting medium, particularly heavy oil, into the top of the generator during subsequent run periods.

The instant invention is particularly an improvement in the processes of manufacturing carbureted water gas shown, described and claimed in U. S. Patents Nos. 2,216,055 and 2,216,056, issued September 24, 1940, upon inventions of Wil-

2

liam E. Steinwedell, in which heavy oil sprayed upon the top of the fuel bed is utilized as a carbureting medium, and in which a downward air-blasting through the fuel bed with air admitted to the top of the generator is also utilized.

The instant improvements have particular advantages at times when hard fuels such as coke derived from soft coal are difficult to obtain or unusually expensive, and gas manufacturers must of necessity rely more on soft fuels.

The annexed drawing and the following description set forth in detail certain steps illustrating my improved process, these steps constituting, however, but a few of the various series of steps by which the improved process may be worked.

The figure is a view, partly in elevation and partly in vertical section, of apparatus for manufacturing carbureted water gas by the use of my improved method.

Referring to the annexed drawing, a generator A, carbureting apparatus such as a carburetor B and a superheater C, and a seal D, are connected together in the well-known manner by a pipe E between the top of the generator A and the top of the carburetor B, a pipe F between the bottoms of the carburetor B and the superheater C, a pipe G leading from the stack C' of the superheater C to the seal D, and a by-pass pipe H from the bottom of the generator A to the pipe G. The aforesaid elements represent a conventional assembly for the manufacture of carbureted water gas by one of the well-known back-run methods of manufacture, and as assisting to this end, a pipe I controlled by a valve I' serves to supply air from a main blast supply (not shown) to the bottom of the generator A, and pipes 2 and 11 controlled by valves 2' and 11', respectively, serve to supply air to the top of the carburetor B from the main blast supply. A further blast pipe 12, which derives air from the main blast supply and is controlled by a valve 12', communicates with the top of the generator A adjacently above the top of the fuel bed, this pipe 12 having, according to the size of the gas-making set, multiple branches 13, if desired and needed, the annexed drawing showing for illustrative purposes two of these branches 13 which feed into opposite sides of the generator A adjacently above the top of the fuel bed. This blast pipe 12 serves as a part of the means by which in my improved method the bituminous coal fuel may be carbonized to coke and the top of the bed of soft fuel may be maintained sufficiently hot to counterbalance the

cooling effect of the carbureting medium sprayed into the top of the generator during the run.

Steam pipes 4 and 8 controlled by valves 4' and 8', respectively, feed into the air pipe 1 and the top of the generator A. The steam pipe 4 serves also in some of its functions as means by which the improved procedures of the instant application can be worked.

An alternate steam pipe 9 controlled by a valve 9' feeds into the pipe G. A pipe 5 controlled by a valve 5' provides means for spraying the carbureting medium, preferably heavy oil, into the top of the generator upon the top of the fuel bed. The form of gas-making set shown is one in which the hot gas valves for controlling the direction of flow are located adjacent the seal D so an up-run hot gas valve 1 controls the pipe G, and a down-run hot gas valve 6 controls the pipe H, whereby a form of back-run carbureted gas manufacture can be worked. The superheater stack C' is controlled by a valve 3. The dip of the pipe G into the seal D is in an amount sufficient to exceed the effect of the pressure in the stack C'. An additional stack 10 is provided which communicates with the pipe H and is controlled by a valve 10'.

The top of the fuel bed J is indicated by j, and this top layer of fuel is designed to represent a fresh fuel charge put into the generator, and will serve to explain some of the steps of the improved procedure hereinafter fully outlined.

The manner of using the aforescribed apparatus, when working the improved process, will now be described. Assuming that a fresh charge *j* of fuel into the generator A is called for, such charging is effected, and then the generator bottom steam pipe 4 is opened a small amount whereby the bottom of the generator A is filled with steam as a matter of safety and a slight upward flow of blue gas through the generator fire is effected which assists in carbonizing the freshly charged bituminous coal. Then the air valve 12 leading to the generator above the fuel bed is opened which effects a burning of the small amount of blue gas passing upwardly through the fuel bed and also of the coal gas which is generated by the heat of the generator fire, the generator walls and the up-coming blue gas. This burning of the blue gas and the coal gas in the top of the generator creates additional heat in such top and assists in carbonizing the freshly charged coal and preparing the generator fire for spraying the carbureting medium, preferably heavy oil, into the top of the generator A during subsequent run periods. Then the air valve 12 is closed, the blast pipe 1 leading to the bottom of the generator A is opened, and the steam pipe 4 closed. Then the carbureter blast pipe 2 is opened, it being assumed that during the procedure just described all valves are closed except the stack valve 3 and the up-run hot gas valve 7 and the other valves whose manipulation has been mentioned. The upward blasting of the fuel bed in the generator A resulting from the opening of the blast pipe 1 effects the production of producer and distilled coal gases which pass through the connection E from the top of the generator A to the top of the carbureter B and are burned by air admitted through the carbureter blast pipe 2, this burning of the blast gases suitably heating the checkerwork in the carbureter B and the superheater C. The resultant products are discharged through the open valve 3 of the stack C'. Then the carbureter blast valve 2' is closed and, in succession, the generator up-blast valve 1' and

the superheater stack valve 3, which places the apparatus in condition for an up-gas-making run.

This up-run is effected by opening the steam valve 4' which results in the formation of blue water gas by the passage of steam through the heated fuel bed, which blue gas is carbureted by a suitable medium, preferably heavy oil, admitted by opening the valve 5', the heavy oil being sprayed upon the top of the fuel bed and being cracked and volatilized and mixing with the blue water gas issuing from the fuel bed. This cracking of the heavy oil is expedited by the heat stored in the generator side wall and the heating of the top of the fuel bed which have in part been effected by the described burning or blue water gas and coal gas generated immediately subsequent to the putting of the freshly charged fuel into the generator A. The cracked and volatilized heavy oil mixed with the blue water gas passes through the connection E to the carbureter B and thence to the superheater C and is permanently fixed by the heated checkerbrick. As has been stated, the hot gas valve 7 in the pipe G is open so that the resultant gases pass into the seal D. The up-gas-making run is terminated by first closing the oil valve 5' and then the up-run steam valve 4'.

Then a down-gas-making run is effected by first opening the down-run hot gas valve 6, and then closing the up-run hot gas valve 7, and then opening the down-run steam valve 8', which results in the formation of blue water gas by the passage of steam downwardly through the fuel bed J, which blue water gas issues from the bottom of the generator A and passes by pipe H into pipe G and thence into the seal D. The down-run is terminated by closing the steam valve 8'.

Then, preferably, before manipulating the several valves in proper positions for up-blasting to commence another cycle, a down or reverse blasting is effected by first opening the valve 10' of the auxiliary stack 10, and then opening the blast valve 11' at the top of the carbureter B, which effects a down-blast through the fuel bed of the generator A, the resultant products passing from the bottom of the generator A into the pipe H and thence into stack 10 and out through the stack valve 10'. The down-blast is terminated by closing the blast valve 11'. Then the up-run hot gas valve 7 is opened, the down-run gas valve 6 closed, the superheater stack valve 3 opened, and the stack valve 10' closed.

The additional heat that is created in the top of the generator, to counterbalance the cooling effect of the oil sprayed thereinto, as has been described, may be created after the charging of the generator A with fresh fuel for one or more blow periods. Therefore, if it is created for more than one blow period, this heating is again effected after the termination of the down-blast. If the down-blast is not utilized, and this heating is utilized for more than one blow period, it will be utilized after the termination of the down-gas-making run. Assuming that these special heating effects have been completed for any one freshly charged batch of fuel, and the regular cycle completed, then the apparatus is in condition for upward blasting of the generator fuel bed which commences the next cycle.

An important refinement of the general process herein described consists in admitting a small amount of steam to the bottom of the generator A concurrently with the upward air-blasting. This steam is comparatively small in volume, preferably five to ten percent of the amount ad-

mitted for the usual up-steam-gas-making run, and is made available, of course, by opening the valve 4' in the pipe 4 a suitable amount. Of course, if the additional heat is being created in the top of the generator A subsequent to a fresh charging of the generator A, the valve 4' will already be open. The stem is admitted to the bottom of the generator A for only a comparatively small part of the upward air-blasting period, and is admitted during the initial part of this upward air-blasting period. The blue water gas produced by passage of this steam through the heated fuel bed improves the heating results, particularly the heating of the top of the fuel bed, and also enhances the storing of heat by radiation in the generator side wall. These improvements are effected by driving the sensible heat of the fuel bed to the upper part of the generator.

Under some conditions, it may be deemed essential to effect a short blast-run during the up-blast. This may be effected by closing the superheater stack valve 3 before the bottom generator blast valve 1' is closed, thus terminating the up-blast period by a short blast-run.

Under some conditions, it may be deemed essential to add carbureting medium to the fuel bed during part of the down-gas making run, as well as to carburet the blue water gas during the up-gas-making run; in which case, the oil pipe valve 5' instead of being closed at the termination of the up-gas-making run, is allowed to remain open during part of the following down-gas-making run, this oil valve 5' then being closed at any desired time after opening the steam valve 8' which initiates the down-gas-making run.

Under some conditions, it may be desired to make a short down-blast run; in which case, the blast valve 11' adjacent the top of the carbureter B which admits the air for down-blasting through the generator A may be opened after the termination of the down steam run, and before the opening of the auxiliary stack valve 10', and thus the down-blast gases created by the passing of the air blast through the valve 11' and thence downwardly through the fuel bed in the generator A pass from the bottom of the generator A through the connections H and G to the seal D for a short period. After such short down-blast run, the auxiliary stack valve 10' is opened and the products of the down-blast pass out through the stack 10.

The improved process can be worked by admitting the steam for the down or reverse gas-making run at the top of the superheater C instead of at the top of the generator A. In this case, the steam pipe 9 controlled by the valve 9' is utilized instead of the steam pipe 8 controlled by the valve 8'. Under these conditions, the gas-making set would be operated under the well-known back-run process of making carbureted water gas. By such operation, the steam passes from the pipe 9 into the connection G and thence into the superheater C and carbureter B in succession, whence it passes through the connection E into the top of the generator A and downwardly through the fuel bed in the operating manner before described with reference to the ordinary admission of steam through the pipe 8 to the top of the generator A. The resultant blue water gas passes from the bottom of the generator A by connections H and G to the seal D.

The over-blasting of the fuel bed to burn blue gas and coal gas in the top of the generator A and to create additional heat therein, after the charging of a fresh batch of fuel, produces a hot,

luminous flame which heats the top of the fuel bed by radiation and stores heat in the side wall of the generator A, thus improving conditions for proper cracking of the carbureting medium sprayed upon the top of the fuel bed at the time of the up-gas-making run.

What I claim is:

1. In processes of manufacturing carbureted water gas, in a gas-making set which includes a generator, carbureting apparatus, a conduit connecting the generator and the carbureting apparatus, and flow-direction control valves, and in which a known cycle of operations consists in first upwardly blasting the fuel bed in the generator with air admitted at the bottom of the generator and burning the blow gases in the carbureting apparatus with air admitted to the latter and passed therethrough, then effecting a steam run upwardly through the fuel bed with steam admitted at the bottom of the generator and simultaneously spraying heavy oil upon the top of the fuel bed and passing the resultant gaseous products through the carbureting apparatus, and then effecting a steam run downwardly through the fuel bed with steam admitted at the top of the generator and withdrawing the resultant gaseous products from the bottom of the generator, the improvements which consist, in using soft fuel as a preponderant percent of the generator fuel, periodically charging fresh fuel into the top of the generator, and after charging fresh fuel in effecting the following steps before the blasting phase of at least the first of the subsequent cycles: admitting a small amount of steam to the bottom of the generator and overblasting the fuel bed with air admitted to the generator adjacently above the fuel bed to burn in the top of the generator the blue water gas and the coal gas thus generated therein, thus creating additional heat in the top of the generator and insuring the carbonizing of the soft fuel charged thereto.
2. The process, as set forth in claim 1, in which the known cycle of operations includes, subsequent to the downward steam run, a downward blasting through the fuel bed with air admitted to the top of the generator and the removal of the blast gases thus generated from the bottom of the generator.
3. The process, as set forth in claim 1, in which said admittance of a small amount of steam to the bottom of the generator is continued into and through a part of the upward air-blasting of the fuel bed.
4. The process, as set forth in claim 1, in which the admittance of a small amount of steam to the bottom of the generator is also effected through a comparatively small initial part of the upward air-blasting of the fuel bed.
5. The process, as set forth in claim 1, in which the known cycle of operations includes, subsequent to the downward steam run, a downward blasting through the fuel bed with air admitted to the top of the generator and the removal of the blast gases thus generated from the bottom of the generator, and in which during a short initial period of this downward blasting the flow-direction control valves are set to effect a down-blow run.
6. In processes of manufacturing carbureted water gas, in a gas-making set which includes generator, carbureter, and superheater shells, and a seal, conduits connecting said shells and seal in series, a conduit connecting the generator and the seal, and flow-direction control valves disposed in

the respective conduits between the superheater and the seal and the generator and the seal, and in which a known cycle of operations consists in first upwardly blasting the fuel bed in the generator with air admitted at the bottom of the generator and burning the blow gases in the carbureter and superheater with air admitted at the top of the carbureter, and exhausting the waste gases from the set, then effecting a steam run upwardly through the fuel bed with steam admitted at the bottom of the generator and simultaneously spraying heavy oil upon the top of the fuel bed, and passing the resultant gaseous products through the carbureter and superheater to the seal, then effecting a steam run downwardly through the fuel bed with steam admitted at the top of the generator and conducting the resultant gaseous products directly from the bottom of the generator to the seal, and then blasting downwardly through the fuel bed with air admitted to the top of the generator and exhausting the blast gases from the bottom of the generator, the improvements which consist, in using soft fuel as a preponderant percent of the generator fuel, periodically charging fresh fuel into the top of the

10

15

20

25

generator, effecting the following operations subsequently to the charging of fresh fuel and prior to the blasting phase of at least one of the cycles immediately following: admitting a small amount of steam to the bottom of the generator and overblasting the fuel bed with air admitted to the generator adjacently above the fuel bed to burn in the top of the generator the blue water gas and the coal gas thus generated therein, thus creating additional heat in the top of the generator and insuring the carbonizing of the soft fuel charged thereto.
